(57) **CLAIM**

The ornamental design for a table as shown and described.

DESCRIPTION

FIG. 1 is a perspective view of a first embodiment of the table embodying the design, in an unextended position.

FIG. 2 is a first side view of the table of FIG. 1, in the unextended position.

FIG. 3 is a second side view of the table of FIG. 1, in the unextended position.

FIG. 4 is a front view of the table of FIG. 1, in the unextended position.

FIG. 5 is a rear view of the table of FIG. 1, in the unextended position.

FIG. 6 is a top view of the table of FIG. 1, in the unextended position.

FIG. 7 is a bottom view of the table of FIG. 1, in the unextended position.

FIG. 8 is a perspective view of the table of FIG. 1, in an extended position.

FIG. 9 is a first side view of the table of FIG. 1, in the extended position.

FIG. 10 is a second side view of the table of FIG. 1, in the extended position.

FIG. 11 is a front view of the table of FIG. 1, in the extended position.

FIG. 12 is a rear view of the table of FIG. 1, in the extended position.

FIG. 13 is a top view of the table of FIG. 1, in the extended position.

FIG. 14 is a bottom view of the table of FIG. 1, in the extended position.

FIG. 15 is a perspective view of a second embodiment of the table embodying the design, in an unextended position.

FIG. 16 is a first side view of the table of FIG. 15, in the unextended position.

FIG. 17 is a second side view of the table of FIG. 15, in the unextended position.

(Continued)

FIG. 18 is a front view of the table of FIG. 15, in the unextended position.

FIG. 19 is a rear view of the table of FIG. 15, in the unextended position.

FIG. 20 is a top view of the table of FIG. 15, in the unextended position.

FIG. 21 is a bottom view of the table of FIG. 15, in the unextended position.

FIG. 22 is a perspective view of the table of FIG. 15, in an extended position.

FIG. 23 is a first side view of the table of FIG. 15, in the extended position.

FIG. 24 is a second side view of the table of FIG. 15, in the extended position.

FIG. 25 is a front view of the table of FIG. 15, in the extended position.

FIG. 26 is a rear view of the table of FIG. 15, in the extended position.

FIG. 27 is a top view of the table of FIG. 15, in the extended position; and,

FIG. 28 is a bottom view of the table of FIG. 15, in the extended position.

Portions of the table shown in broken lines are for illustrative purposes only and form no part of the claimed design.

1 Claim, 28 Drawing Sheets
